PLIER WRENCH

Milton W. Emmett, Los Angeles, Calif.

Application October 29, 1942, Serial No. 463,786

5 Claims.

(Cl. 81—86)

This invention relates to pliers and wrenches and the general object of the invention is to provide an improved plier and wrench with means for automatically locking its jaws upon the work to which said jaws are applied and with means whereby said jaws may be readily moved apart to release them from the work as desired.

Another object is to provide a plier and wrench of the character stated which may be used to advantage as a clamp.

A further object is to provide a strong and durable plier and wrench of the character stated which is easy to handle and efficient in operation.

Other objects and advantages will appear hereinafter.

The invention is illustrated in the annexed drawing which forms a part of this specification and in which,

Fig. 1 is a side view of my plier and wrench, partly broken away to show certain features of construction thereof.

Fig. 2 is an edge view of my plier and wrench.

Fig. 3 is a transverse section of my plier and wrench taken on line 3—3 of Fig. 2.

Fig. 4 is a fragmentary sectional view taken on line 4—4 of Fig. 2, showing one side of the shank of the movable jaw and one side of the guideway of my plier and wrench in which guideway said shank is slidably mounted.

Fig. 5 is a fragmentary plan view of the guideway for the shank of the movable jaw.

Fig. 6 is a fragmentary inner edge view of the shank of the movable jaw.

Referring more particularly to the drawing, in which corresponding parts are designated by the same reference numerals in all of the figures, my plier and wrench includes a body 1, a pair of jaws 2 and 3, which jaw 2 is integral with said body, a pair of plier handles 4 and 5, which handle 4 is integral with said body 1, a shank 6 extending from jaw 3 and slidably mounted in a guideway 7 in said body 1, a rack 8 along the inner edge of said shank, a gear 9 of magnetic material in mesh with said rack, turnably mounted on a shaft 10 secured in said body 1, on which shaft the inner end of the handle 5 is fulcrumed, and a lock 11 mounted in said handle 5 for engaging the teeth of said gear 9 and locking said handle to said gear.

The sides 12 of the shank 6 of jaw 3 are beveled, diverging inwardly, and are slidably fitted to the inner sides 13 of the guideway 7, which inner sides are beveled correspondingly to the beveled sides 12 of said shank 6. The sides 12 of the shank 6 are knurled, as indicated at 14, in Fig. 4,

and the inner sides 13 of the guideway 7 are knurled, as indicated at 15 in said figure, so that the sides 12 of said shank may effectively bind against the inner sides 13 of said guideway, in the manner and for the purpose hereinafter more fully described. The gripping edges 16 and 17 respectively, of the jaws 2 and 3 extend longitudinally of my plier and wrench, while the shank 6 of jaw 3 and the shank guideway 7 extend at an obtuse angle of substantially ninety-five (95°) degrees to said gripping edges of said jaws forwardly of the gripping face of the movable jaw, i. e. to the right in Fig. 1 to facilitate a wedging action between the sides 12 of the shank 6 of jaw 3 and the inner sides 13 of the guideway 7, in the manner hereinafter more fully described.

The body 1 is formed with a slot 18 to receive the gear 9, in mesh with the rack 8, and the inner end portion 19 of the handle 5, which inner end portion of said handle is forked, and its fork members 20 straddle said gear 9, with the shaft 10 extending freely through openings 21 in the inner ends of said fork members, whereby the inner end of the handle 5 is fulcrumed on said shaft, the fork members 20 fitting closely, but freely between the sides of the gear 9 and the sides of the slot 18 so that the inner forked end portion 19 of the handle 5 may be swung freely between said gear and the sides of said slot. The ends of the shaft 10 are secured in the walls 22 of the body 1 at the sides of the slot 18 in said body.

In the handle 5 is mounted the lock 11 for locking said handle to the gear 9, so that said gear 35 will be turned, upon swinging said handle on its fulcrum 10, whereby said gear, in mesh with rack 8, may move the jaw 3 toward or away from the jaw 2. The lock 11 comprises a plunger 23, slidably mounted in a bore 24 in the handle 5, a toothed latch 25 on the inner end of said plunger, and a spring 26 for normally thrusting said plunger forwardly and said toothed latch into mesh with the teeth 27 of the gear 9, the teeth 28 of said latch corresponding to the teeth 27 of said gear. The plunger 23 is formed with a reduced shank 29 extending rearwardly through the bore 24 and out of the handle through a short reduced bore 30 in said handle at the rear end of the bore 24. The spring 26 surrounds the plunger shank 29 in the bore 24 and bears at its rear end against the rear end of the plunger bore 24 and at its forward end against the rear end of the plunger 23. The latch 25 is a permanent magnet which will draw itself into mesh with the teeth of the gear 9 and lock said gear to the

handle 5, irrespective of the action of the spring 26, thus ensuring engagement of said latch with the teeth of said gear in the event of failure of said spring. A pin 31 extends laterally from one side of the shank 29 through a slot 32 in one side of the handle 5, by means of which pin the plunger 23 and said latch may be moved rearwardly against the tension of the spring 26 and the teeth of said latch withdrawn from the teeth of the gear 9 to unlock said gear from the handle 5.

The operation of my invention is as follows:

The handle 5 being locked to the gear 9 by the lock 11, said handle is swung outwardly on its fulcrum 10 away from the handle 4, whereupon the gear 9 is turned counterclockwise (Fig. 1), so that said gear, in mesh with the rack 8, will move the jaw shank 6 to the left in the guideway 7, and the jaw 3 will be moved correspondingly, away from the jaw 2, a sufficient distance to receive the work between said jaws. The jaws 2 and 3 are then slipped over the work, such as a nut or other object, and the handle 5 is swung on its fulcrum 10 toward the handle 4, whereupon the gear 9 is turned by the handle 5 clockwise (Fig. 1) so that said gear, in mesh with the rack 8 will move the jaw shank 6 to the right in the guideway 7, and the jaw 3 will be moved correspondingly toward the jaw 2, until said jaws grip the work firmly therebetween. The grip of the jaws 2 and 3 upon the work tends to swing the jaw 3 backwardly and the jaw shank 6 upwardly from the forward lower corners 33 of the guideway 7, which action of the jaw 3 causes the lower edges of said shank to bind against said forward lower corners 33 of said guideway and the beveled sides 12 of said shank 6 to wedge at the rear end of the shank against the beveled inner sides 13 of the guideway 7, as indicated at 34 in Fig. 1, which binding and wedging action of said shank locks the jaws 2 and 3 positively upon the work, so that said jaws will hold onto the work, if the handles 4 and 5 are released, until the handle 5 is swung away from the handle 4 to move the jaw 3 away from the jaw 2, through the medium of the gear 9 and rack 8.

The arrangement of the shank 6 and guideway 7 at an angle of 95 degrees assists the wedging action of the rear end portion of the shank 6 in the guideway 7 for locking the jaws 2 and 3 gripped upon the work.

The knurled side faces 14 and 15 of the jaw shank and the guideway cause said faces to engage each other with considerable friction, when wedged together and assist materially in locking the jaws 2 and 3 upon the work.

By means of the pin 31 the latch 25 may be moved rearwardly in the handle 5 against the tension of the spring 26 and against the magnetism of the latch 25, and the teeth 28 of said latch withdrawn from between the teeth 27 of the gear 9, to unlock said gear from the handle 5, so that the jaw 3 may be moved away from or toward the jaw 2 independently of the handle 5, the gear 8 being turned freely by the rack 8 as the jaw 3 is moved as aforesaid.

I do not limit my invention to the exact construction disclosed herein, since various changes may be made therein without departing from the spirit of the invention.

The inner edges of the guideway 7 are knurled, as indicated at 35, and the inner edges of the shank 6 are knurled, as indicated at 36, for engaging the knurled edges 35 of the guideway to

enable said engaging edges to bind with greater friction to prevent opening of the jaws 2 and 3.

I claim:

5. A plier wrench comprising a body formed with a fixed jaw, a guideway and a fixed handle, a movable jaw formed with a shank slidably mounted in said guideway, so that said movable jaw may be moved toward or away from said fixed jaw, a rack on said shank, a gear turnably mounted in said body in mesh with said rack, a swingable handle fulcrumed in said body about the axis of said gear to swing toward or away from said fixed handle, and means for locking said handle and said gear together to enable said handle to turn said gear, said locking means comprising a magnetic latch slidably mounted in said swingable handle to draw itself into locking engagement with the teeth of said gear.

20. A plier wrench comprising a body formed with a fixed jaw, a guideway and a fixed handle, a movable jaw formed with a shank slidably mounted in said guideway so that said movable jaw may be moved toward or away from said fixed jaw, a rack on said shank, a gear turnably mounted in said body in mesh with said rack, a swingable handle fulcrumed in said body about the axis of said gear to swing toward or away from said fixed handle, and means for locking said handle and said gear together to enable said handle to turn said gear, the sides of said jaw shank and said guideway being beveled and knurled so that said shank will bind in said guideway when said jaws grip an object.

25. A plier wrench comprising a body formed with a fixed jaw, a guideway and a fixed handle, a movable jaw formed with a shank slidably mounted in said guideway so that said movable jaw may be moved toward or away from said fixed jaw, a rack on said shank, a gear turnably mounted in said body in mesh with said rack, a swingable handle fulcrumed in said body about the axis of said gear to swing toward or away from said fixed handle, a latch comprising a permanent magnet formed with a pair of teeth and slidably mounted in said swingable handle whereby the latch will draw itself toward said gear and its teeth into mesh with the teeth of said gear.

30. A plier wrench as claimed in claim 3 including a spring mounted in said swingable handle for urging said latch into engagement with said gear.

35. A plier wrench comprising a body formed with a fixed jaw, a guideway and a fixed handle, a movable jaw formed with a shank slidably mounted in said guideway so that said movable jaw may be moved toward or away from said fixed jaw, said shank and said guideway being arranged at an obtuse angle of substantially 95 degrees to the gripping faces of said jaws forwardly of the gripping face of said movable jaw, and the sides of said shank and said guideway being knurled and converged outwardly for locking said jaws upon the work, when said jaws are moved together upon the work, a rack on said shank, a gear turnably mounted in said body in mesh with said rack, and a swingable handle fulcrumed in said body about the axis of said gear to swing toward or away from said fixed handle, and means for locking said handle and said gear together to enable said handle to turn said gear.
